UNITED STATES PATENT OFFICE.

HENRY P. HART, OF DETROIT, MICHIGAN.

DESIGN FOR A HAT-HOOK.

SPECIFICATION forming part of Design No. 32,763, dated May 29, 1900.

Application filed February 15, 1900. Serial No. 5,388. Term of patent 3½ years.

To all whom it may concern:

Be it known that I, HENRY P. HART, of Detroit, in the county of Wayne and State of Michigan, have invented and produced a new and original Design for Hat-Hooks, of which the following is a specification, reference being had to the accompanying drawing, forming part thereof.

The figure is a perspective view of a hat-hook, showing my new design.

As shown in the drawing, the leading or material feature of my new design consists of two plain-surfaced limbs A and B, branching outward and upward at equal angles and surmounted by plain-surfaced knobs *a* and *b*. At the junction between said limbs is a plain flat-surfaced shield C, having plain-surfaced flanges *c* extending backward from around its edges. The limbs A and B appear to proceed from back of said shield at its upper corners, where the flanges *c* and a part of the surface of the shield appear to be cut away to permit their passage. From the lower flanges *c* near

the lower corners of said shield extend two horn-like projections D E, which extend downward and sidewise and then bend upward. At the base of said horn-like projections is a flat flange F, extending between said projections and united at its upper edge with the flange *c*. The lower edge of the flange F is curved downward between the two projections D E, and the surface of said flange is slightly ornamented along said edge.

Having described my invention, what I claim as new, and desire to secure by Letters Patent, is—

The design for a hat-hook, substantially as shown and described.

In testimony whereof I have signed my name to this specification in the presence of two subscribing witnesses.

HENRY P. HART.
